BRAKE HANGER SUPPORT

Filed May 23, 1927

UNITED STATES PATENT OFFICE

VICTOR H. HARBERT, OF CHICAGO, ILLINOIS, ASSIGNOR TO E. PAYSON SMITH, OF CHICAGO, ILLINOIS

BRAKE-HANGER SUPPORT

Application filed May 23, 1927. Serial No. 193,400.

My invention relates to supports whereby the hangers for the brakes of a railroad car are pendently supported from the truck frame which is preferably provided with a suitable projection or arm, having one side thereof adjacent to the outer end formed to provide a suitable laterally disposed socket adapted to receive the keeper means for holding the support in place.

10 The invention also involves means whereby the keeper means are firmly locked in place; the construction being such that keeper means of smaller dimensions,—comprising a pair of complementary blocks,—may be 15 employed, thereby creating a great saving in material and expense, while still possessing the requisite strength and bearing surface for the hangers or hanger supporting pins.

The objects and advantages of my invention will be readily comprehended from the detailed description of the accompanying drawing, wherein—

20 Figure 1 is a side elevation of my improved support and an arm on a truck frame of which only a portion is shown in section and merely the upper end of a hanger being shown.

Figure 2 is a vertical sectional view taken on the line 2—2 of Figure 1 looking in the direction of the arrows.

25 Figure 3 is a cross section taken on the line 3—3 of Figure 2 looking in the direction of the arrows.

Figure 4 is a perspective view of one of a pair of similar members constituting the hanger keeper means.

Figure 5 is a view substantially similar to Figure 1 showing the use of a modified form of keeper means.

Figure 6 is a horizontal sectional view of 40 the structure shown in Figure 5.

The embodiment of the invention as shown in the first four figures of the drawing is especially adapted for use in connection with the continuous or closed link type of brake hanger, a part whereof is shown at 10. The truck frame 11 is preferably provided with a projection or arm 12, the outer end whereof is enlarged laterally in order to permit the same to be slotted or socketed, thereby providing the upper and lower walls 13 and 14, re-

spectively, connected at their inner ends by the vertical webs 15, which are preferably made arcuate as shown in dotted lines at 16 in Figure 2 in order to conform with the arcuate surfaces 17, 17, adjacent the ends of the keeper blocks 18. The slot or socket in the end of the arm 12 is preferably made at a slight inclination as more clearly shown in Figure 2, so as to induce the keeper means to slide downwardly with the rounded portions 17, 17 seated on the arcuate webs 15. It is apparent from this construction that accidental displacement of the keeper means, in the event of loss of the locking means, is less likely, while at the same time the strains placed on the keeper means will all be transmitted to the truck frame arm.

20 The keeper means consists of a pair of blocks identical to that shown in Figure 4; each preferably provided with the projection 70 or shoulder 19, intermediate of the arcuate surfaces 17, 17 on the inner or rear side of the blocks. These shoulders are intended to extend into the recess 20 in the arm intermediate of the webs 15, 15, and thereby prevent shifting of the keeper means in a direction lengthwise of the blocks. Each block 18 on its apposite face is provided with the longitudinally disposed groove 21 intended to receive the upper end of the brake hanger 10; 75 the grooves 21 of the two blocks, when arranged in face to face relation as shown in Figure 2, being sufficient to receive the link 10 and still permit free oscillation of the link when the blocks are in juxtaposition.

25 The upper and lower walls 13 and 14 are each provided with a slot disposed at right angles to the main portion of the arm 12; that is to say the slots extend lengthwise of the socket. The slot 22 in the upper wall 13 is somewhat longer than the slot 23 in the lower wall 14; and the inner ends of both slots are made sloping outwardly or forwardly toward the bottom at an angle substantially similar to the angle of inclination of 95 the keeper blocks.

These slots 22 and 23 are so arranged that the inner ends thereof will be disposed in a vertical plane rearward of the forward edges of the keeper elements when the latter are 100

completely seated in the socket formed in the arm 12, see Figure 2. The forward longitudinal sides of the keeper members 18 (which are arranged in superposed relation) are each provided with a vertically disposed groove or slot as shown at 24, see Figure 4, for the purpose of receiving the rear edge of the wedge member or key 25 when the latter has been driven through slots 22 and 23 in the arm portions or walls 13 and 14. The forward longitudinal edge of the wedge member or key 25 is intended to be disposed perpendicular to the ends of the wedge member while the rear longitudinal edge is made sloping so as to provide a key member tapering toward the lower end thereof.

In practice, the brake hanger 10 has its upper end inserted into the groove 21 of the lower keeper member or block 18; the upper block 18 is then put into position with its grooved face downwardly so that the grooves 21 of the two blocks constitute a suitable channel for the upper end of the hanger 10. The assembled elements are then inserted into the socket formed between the upper walls 13 and 14, with the shoulders 19 disposed into the rear end of the socket intermediate of the vertical webs 15 between walls 13 and 14. These shoulders not only center the blocks in proper position, but also prevent lateral or sidewise movement thereof. The key member or wedge 25 is then driven into place with its tapered end disposed downwardly thus causing the forward perpendicular edge to be in bearing relation with the forward ends of the slots 22 and 23 while the sloping rear edge of the key member, which is disposed in the grooves 24 of both blocks, will be in bearing relation with the forward surfaces of the blocks, without contact at the rear ends of the slots 22 and 23. This causes the blocks to be firmly wedged in place. It is understood that the hanger 10 straddles the lower wall portion 14. After the key has been firmly driven into place, the lower end thereof is preferably flexed or bent laterally as shown at 26 in Figure 1 so that accidental removal of the key is prevented.

In Figures 5 and 6, I show a modification especially intended for use in connection with the U-shape hanger indicated at 27 having upper eyeleted ends 28 to receive a supporting pin 29. The keeper means, in this instance, consists of a pair of corresponding blocks 30, 30 of somewhat greater length than the blocks or keeper members 18. The ends of blocks 30, 30 are preferably slightly enlarged as shown at 31 and slotted transversely from the rear sides to receive the eyeleted ends 28 of the hanger 27 and still permit oscillatory movement of the hanger. These slotted ends are disposed beyond the vertical webs 15, 15 of the arm 12 whereby the upper and lower walls 13 and 14 are connected together. The apposite faces of each member

or block 30 is provided with a longitudinal groove disposed throughout the intermediate or main body portion as well as partially into the ends to receive the supporting pin 29. The pin receiving grooves terminate a short distance from the immediate ends of the blocks so as to provide the abutting walls 32, 32 at the ends of the pin 29 and thus prevent longitudinal movement of the latter.

It will be understood that the keeper members or blocks 30 are identical in construction and like blocks 18 are interchangeable. That is to say, either block may constitute the upper or lower block. The forward longitudinal sides of the blocks 30 are each provided at a registering point with a vertically disposed groove 33 adapted to receive the wedge member or key 25 when the latter is disposed through slots 22 and 23 formed in the upper and lower wall portions 13 and 14 like in the previously described construction. The wedge member 25, for the construction shown in Figures 5 and 6, as well as the function of the slots 22 and 23 are identical with that previously described.

In practice, the supporting pin 29 is inserted through the eyelets 28 of hanger 27, the pin 29 then placed in the longitudinal groove of the lower block 30 after which the upper block 30 is placed thereon with its longitudinal groove encircling the upper side of the supporting pin; the end walls 32 of both blocks completely closing the ends of the groove and preventing movement of the pin. The assembled elements are then put into the socket in the arm intermediate of the walls 13 and 14 with the hanger 27 straddling the lower wall portion 14 like in the previously described construction. The wedge member or key 25 is then driven downwardly through the slots 22 and 23 with its rear sloping edge in the grooves 33 of the keeper members or blocks. The slots 22 and 23, as previously described, are of such length that their rear ends are disposed in a vertical plane rearward of the vertical forward longitudinal edges of the keeper elements or blocks so that the wedge member or key will not contact with the rear ends of the slots 22 and 23. This permits a firm wedging of the keeper blocks in place. The lower end of the wedge member or key is then preferably flexed or bent laterally as shown in Figure 5 at 26 to hold the wedge member firmly in place.

It is apparent that other means may be used for locking the wedge member in place, but the method shown is believed to be the simplest and most acceptable, because the necessity for employing additional parts or elements is eliminated.

With my constructions it is apparent that if any wear should result between the keeper members or blocks and the cast metal portions of the truck frame, this can be readily

taken up by adjustment or further driving of the wedge member into place. Furthermore, the wedge member or key when properly driven home will prevent all chatter or vibration between the keeper member and the truck frame and thus materially reduce possibility of wear. Furthermore, with my improved construction, a considerable saving in material and expense is possible because the method of securing the keeper means in place enables narrower keeper blocks to be employed than has heretofore been the case.

In order to permit the temporary use of an ordinary brake pin or bolt, in the event of loss of the wedge key 25 while the train is at a distance from the shops, I show the intermediate portions of slots 22 and 23 in the upper and lower walls 13 and 14, bowed outwardly or made arcuate as shown at 34 to provide an opening sufficiently large to receive the ordinary round pin which is generally accessible along the right-of-way. The slots 24 in keeper blocks or plates 18, and the slots 33 in the keeper plates 30, at the outer ends, are therefore flared outwardly in an arcuate manner as shown at 35 and 36, respectively, see Figures 4 and 6, to permit the temporary use of an ordinary bolt or pin having a round shank. It is apparent that the round pin will hold the keeper elements with the brake hangers in proper position, permitting proper brake application during the remainder of the run, until a replacement of the wedge key can be made.

The constructions shown are thought to be the simplest and best embodiments of the invention, but certain modifications may be made without, however, departing from the spirit of my invention.

What I claim is:

1. A brake hanger support comprising, in combination with a truck frame provided with a transversely disposed socket open toward the truck wheels, a pair of correlated keeper plates insertible in said socket, the forward sides of said plates and the upper and lower walls of the socket being provided with vertically aligned slots, and a locking key adapted to pass through said slots with its forward edge engaging with said upper and lower walls at the forward ends of the slots therein while the rear edge engages with the keeper plates.

2. A brake hanger support comprising, in combination with a truck frame having a laterally disposed arm, the outer end whereof is provided with a transverse socket open toward the wheels of the truck, the upper and lower walls of the socket being provided with aligned slots disposed lengthwise of the socket, a pair of superposed correlated keeper plates correspondingly grooved on their opposite faces and insertible in said socket, the forward longitudinal edges of said plates being grooved to register with the aligned

slots in the upper and lower walls of the socket, and a bendable wedge member insertible through said slots and the plate grooves whereby said plates are forced into said socket and locked in place.

3. A brake hanger support comprising, in combination with a truck frame having a socket sloping downwardly toward the inner end and open toward the truck wheels, the walls above and below said socket each having a slot extending lengthwise of the socket, a pair of keeper plates insertible in said socket in superposed relation, said plates being formed to receive a supporting hanger and hanger supporting pin therebetween, the walls of said socket and rear longitudinal sides of the plates being formed to prevent transverse movement of the latter, the forward longitudinal sides of the plates being formed to provide vertical slots adapted to register with the slots in the walls of said socket, and a wedge member insertible in the slots of the walls and said plates whereby the latter are locked in place.

4. A brake hanger support comprising, in combination with a truck frame having a socket open toward the truck wheels, the walls above and below said socket having slots disposed in the direction of said open end of the socket, hanger and hanger pin supporting means insertible wholly within said socket, and a wedge key disposed vertically through said slots with the rear vertical face engaging with the outer side of said supporting means whereby the latter is forced toward the inner end of the socket and locked against movement.

5. A brake hanger support comprising, in combination with a truck frame having a socket open toward the truck wheels, keeper means for the brake hanger and hanger supporting pin, insertible in said socket, the walls of the truck frame above and below the socket and the outer vertical side of said keeper means having aligned correlated surfaces, and adjustable means adapted to pass through the walls of the socket and coact with said surfaces of the socket walls and keeper means whereby the latter are forced toward the inner end of said socket and locked in place.

6. A brake hanger support comprising a truck frame having a socket open toward the truck wheels, the walls above and below said socket having registering slots disposed in the direction of said open end of the socket with intermediate portions of said slots being enlarged laterally, complementary hanger and hanger-pin supporting plates, grooved longitudinally on their opposite faces, insertible in said socket, the outer longitudinal sides of said plates being transversely slotted, with the outer ends of said slots flared to register with the enlarged portions of the slots in said walls, and means insertible

through the slots in said walls and in said plates for locking the latter in place.

7. A brake hanger support comprising, in combination with a truck frame provided with a socket open toward the wheels of the truck, the upper and lower walls of the socket at the inner end thereof being united by laterally spaced ribs, while the outer ends of said walls are provided with registering slots disposed in a direction lengthwise of the socket, keeper means insertible into said socket and provided at the inner side with a projection adapted to extend between said spaced ribs to prevent lateral movement of said means, and a wedge-key insertible through said slots, the slots and wedge-key being so formed that the forward side of the key engages the outer ends of the slots while the rear side of the key engages the forward side of said means and forces the latter inwardly as said key is forced downwardly through said slots.
